UNITED STATES PATENT OFFICE

CARL BUSCH THORNE, OF HAWKESBURY, ONTARIO, CANADA

LOG BARKER

Application filed June 27, 1930. Serial No. 464,240.

The invention relates to a log barker, as described in the present specification and illustrated in the accompanying drawings that form part of the same.

5 The invention consists essentially in reciprocating the disturbing members under the pile of logs in order to keep these logs continuously tumbling and rolling in their passage to the discharge, as pointed out in the 10 claims for novelty following a description of an acceptable form of the invention.

The objects of the invention are to strip the bark from the logs gathered together in considerable piles and at the same time maintain the onward movement by facilitating the 15 depletion of the pile at the delivery end, after the logs have had full opportunity to rub sufficiently to be relieved of the bark; to economize in so far as time and labor are concerned 20 and complete the stripping of great quantities of logs in one treatment or a succession of similar treatments and thus avoid much extra handling often required through the return of the logs for further stripping operations; to conserve the power at great plants 25 by minimizing the load, that is to say, where considerable lifting force is required by rolling the logs and effecting the rolling by a contributory rolling motion adapted to turn the 30 logs in a natural movement, and at the same time facilitate their discharge; and generally to relieve the congestion in log piles and provide an efficient and simple means of disturbance.

35 In the drawings, Figure 1 is a plan view of the pocket showing the supporting and disturbing members.

Figure 2 is an elevational view of the operating mechanism as illustrated in Figure 1 40 and showing the pocket containing logs in section.

Figure 3 is a perspective detail of the reciprocating carriage and disturbing members.

45 Figure 4 is an elevational detail of the carriage without the front cross beams.

Figure 5 is a cross sectional view on the line 5—5 in Figure 1.

50 Like numerals of reference indicate corresponding parts in the various figures.

Referring to the drawings, the numeral 15, indicates a pocket having at one end the inclined feed platform 16 down which the logs are rolled into the pocket and at the other end the discharge runway 17, which extends 55 from the end wall 18 inclined towards said runway.

The chains 19 extend from end to end of the pocket at the bottom and are fixedly secured at the ends 20 and 21 and hang between 60 said ends comparatively loose, this slackness being taken up by the disturbing members, indicated by the sprocket wheels 22.

The sprocket wheels 22 are fixedly mounted on the shaft 23 and this shaft is journaled 65 in the carriage 24 at the upper end thereof.

The carriage is formed of the end frames 25 and 26 joined by the cross beams 27 and 28. The upper bearing beams 29 carry the shaft 23 and the lower bearing beams 30 carry 70 the shaft 31, while the legs 32 have the axle bearings 33 for the axles of the carriage wheels 34 which roll on the tracks 35 and 36.

The gears 37 coact on the one hand with 75 the sprockets 22 and on the other hand with the racks 38, these racks being rigidly secured to the ties 39, which also support the tracks or rails 35 and 36, but are within the trackway that is to say, between the rails.

Two of the sprockets 22 are intermediate 80 of the outer sprockets which coact with the racks, therefore it is by means of these racks that the gears 37 are turned, which insures the rotation of the shaft 23 and consequently 85 of the sprockets 22.

The chains 19 operate in the longitudinal openings 40 formed by the spaced beams 41 which constitute the bottom of the pocket between the end walls, and it is between these beams in the openings 40 that the sprockets 22 project upwardly into the pocket and carry the chains so that each chain engages the logs and it is while the sprockets are running along and revolving in the openings 40 so that the rolling motion is imparted to 90 the logs, which are indicated by the numeral 42.

The carriage 24 is drawn backwardly and forwardly, that is to say, it reciprocates and there are of course several ways of recipro- 100

cating this carriage. Perhaps the simplest way to reciprocate this carriage is by means of cable with steam as the power, therefore the steam engine 43 is shown at one end and 5 this steam engine 43 through its pitman 44 and crank 45 operates the shaft 46, carrying the flywheel 47.

The pulley 48 carries the belt 49 and this belt is trained over the pulley 50 mounted 10 on the shaft 51. The shaft 51 carries the bevelled gear 52 which coacts with the bevelled gear 53 mounted on the driven shaft 54. The driven shaft 54 carries the spiral gear 55, which coacts with the shift gear 56. 15 The spiral shift gear 56 is mounted on the hub 57 which constitutes the clutch members 58 and 59, this hub 57 forming a sliding sleeve on the drum shaft 60.

The drum shaft 60 carries the drums 61 20 and 62 and these drums have the coacting clutch members 63 and 64 which have clutch teeth operating in opposite directions respectively, corresponding to the teeth of the clutch members 58 and 59.

25 The cables 65 and 66 are wound on the drums 61 and 62 respectively and the cable 65 extends to and is secured to the eye-bolt 67 rigid with the carriage 24 in the center of the front beam thereof.

30 The cable 66 extends from the drum 62 and is trained over the pulley 68 mounted in a suitable bearing at the upper end of the standard 69 beyond the pocket at the opposite end to the drums.

35 This cable 66 is brought around said pulley and secured to the eye-bolt 70 rigid with the carriage 24 on the opposite side to the eye-bolt 67, consequently when the spiral gear 55 moves the spiral gear 56 in the direction of 40 the drum 61, the clutch member 58 engages the clutch member 63, and this drum 61 is then rotated and winds the cable up thereon, while the drum 62 is free to unwind.

In this way the carriage is pulled towards 45 the drums, but when the engine is reversed, the spiral gear 56 will be moved in the other direction, that is to say, towards the drum 62 and the clutch members 59 and 64 will be in engagement, consequently the drum 61 will 50 be free of the drum 62 in operation.

This will pull on the cable 66 and draw the carriage 24 in the opposite direction, that is to say, on the return passage and these movements will be maintained constantly with the 55 result that the sprockets are rolling along in the openings 40 and carrying said slack chains into the pockets, which has the effect of tumbling the logs in a rolling motion, somewhat similar to what may be called the 60 natural rolling motion of their own, which has the effect of stripping the logs of their bark.

In order to keep this motion up automatically, it is desirable to install the trip rod 71 65 slidably mounted in the brackets 72 and hav-

ing the arms 73 and 74 engaged by the trip arm 75, rigid with the carriage 24.

The rod gear extends through to the reverse lever 76, by means of which the direction of rotation of the engine shaft is reversed. 70

In the operation, the logs are rolled along the feed platform into the pocket and this pocket fills up, and contains a great pile of logs constantly moving into the pocket and 75 constantly moving out of it, as of course the idea of the invention is to handle great quantities.

The reciprocating movement of the carriage 24 accounts for the constant travel of 80 the logs and the stripping thereof while they are in the pocket. The speed of the carriage movement and the extent of the log rolling motions are regulated according to the circumstances of use and the constructional details are arranged accordingly. 85

The carriage is pulled along from one end to the other and back again and the chains engaging on the sprockets roll these logs against one another and tumble them, so that 90 the rubbing takes off the bark and at the same time keeps them in motion through to the delivery end and constantly rolling down the runway.

The feed is of course continuous and therefore 95 the logs have no opportunity at the feed end to back up against the oncoming logs, while the runway at the discharge end is free and naturally the logs find their way along the line of least resistance and the final 100 result is the clean log barked in a way that will not chip it thereby eliminating the loss due to the chipping of logs in rougher machines.

What I claim is:—

1. In a log barker, a log pocket having feed and discharge ends and a bottom having longitudinal openings therein, slack chains secured at each end and extending along said openings and a carriage having driven 110 sprocket members engaging said chains and lifting the logs in said pocket and reciprocating beneath said pocket.

2. In a log barker, a pocket having longitudinal openings in the bottom thereof and rigidly secured slack chains extending along in said openings, a carriage reciprocatively arranged beneath said pocket having suitable shaft bearings therein, a sprocket shaft and sprocket members mounted thereon and supported in said carriage, said sprocket members engaging and lifting said chains in their passage along said openings into said pockets, a gear shaft, gears coacting with said sprockets mounted thereon and supported in 120 said carriage, stationary racks extending along and suitably secured and coacting with said gears and means for reciprocating said carriage under said pocket.

3. In a log barker, a log pocket having 130

feed platform and a discharge runway and intermediately a bottom with longitudinal openings, slack chains rigidly secured at each end and extending along said openings, 5 sprockets engaging and lifting said chains through said openings, a reciprocating carriage having a shaft journalled therein and carrying said sprockets, gears coacting with said sprockets and racks coacting with said 10 gears, rails forming a trackway for said carriage, drums and cables connected with said carriage and forming the means of reciprocating the same beneath said pocket, motive power operatively connected with said 15 drums and means operated by said carriage for reversing the direction of movement thereof at the end of its travel.

Signed at Montreal, Canada, this 6 day of June, 1930.
